US00D798659S

(12) **United States Design Patent** (10) **Patent No.:** **US D798,659 S**
(45) **Date of Patent:** **** Oct. 3, 2017**

(54) **VENTURI DEVICE**

(71) Applicants: **Thomas J Casper**, Waukesha, WI
(US); **Jeffrey Casper**, Minneapolis, MN
(US)

2,241,337 A 5/1941 Work
2,424,654 A 7/1947 Blount
2,899,971 A 8/1959 Munter

(Continued)

(72) Inventors: **Thomas J Casper**, Waukesha, WI
(US); **Jeffrey Casper**, Minneapolis, MN
(US)

BR 8702702 12/2007
CN 201379435 4/2009

(Continued)

(**) Term: **15 Years**

FOREIGN PATENT DOCUMENTS

(21) Appl. No.: **29/581,321**

(22) Filed: **Oct. 18, 2016**

Related U.S. Application Data

(60) Division of application No. 29/530,931, filed on Jun. 22, 2015, now Pat. No. Des. 778,667, which is a continuation of application No. 13/398,391, filed on Feb. 16, 2012, now abandoned.

(51) **LOC (10) Cl.** **07-99**

(52) **U.S. Cl.**

USPC **D7/400; D7/667**

(58) **Field of Classification Search**

USPC D7/396.2, 213, 398, 397, 400, 667, 700,
D7/387; D9/436, 435, 440;
261/DIG. 75, 76; 99/275, 323.1;
222/190; 366/163.2
CPC .. B01F 3/04503; B01F 3/0446; B01F 5/0428;
B01F 3/04794; B01F 2215/0072; B60D
47/32; A47J 31/02

FIG. 1 is a perspective view of a first embodiment of the venturi device;

See application file for complete search history.

FIG. 2 is a front elevation view, the rear elevation view

(56) **References Cited**

being identical;

U.S. PATENT DOCUMENTS

FIG. 3 is a right side elevation view, the left side elevation

141,361 A 7/1873 Korting
513,857 A 1/1894 Adam
846,395 A 3/1907 Busenbenz
1,052,051 A 2/1913 Grimes
1,786,357 A 12/1930 Miller

view being identical;

FIG. 4 is a top plan view thereof;

FIG. 5 is a bottom plan view thereof;

FIG. 6 is a perspective view of a second embodiment of the venturi device;

FIG. 7 is a front elevation view, the rear elevation view

being identical;

FIG. 8 is a right side elevation view, the left side elevation

view being identical;

FIG. 9 is a top plan view thereof; and,

FIG. 10 is a bottom plan view thereof.
